(57) **CLAIM**

We claim, the ornamental design for a dispenser, as shown and described.

DESCRIPTION

FIG. 1 is a side perspective view of a dispenser showing our new design;

FIG. 2 is a top plan view of the dispenser;

FIG. 3 is a side view of the dispenser; and,

FIG. 4 is a bottom plan view of the dispenser.

The broken line showing of the dispenser body is included for the purpose of illustrating and forms no part of the claimed design.

1 Claim, 2 Drawing Sheets
